UNITED STATES PATENT OFFICE.

JAMES W. KNOBLOCK, OF ELMIRA, NEW YORK, ASSIGNOR TO AMERICAN LA FRANCE FIRE ENGINE COMPANY, INC., OF ELMIRA, NEW YORK, A CORPORATION OF NEW YORK.

PORTABLE SEARCHLIGHT.

1,316,246.

Specification of Letters Patent. Patented Sept. 16, 1919.

Application filed July 5, 1917. Serial No. 178,746.

To all whom it may concern:

Be it known that I, JAMES W. KNOBLOCK, a citizen of the United States, and residing at Elmira, in the county of Chemung and 5 State of New York, have invented certain new and useful Improvements in Portable Searchlights, of which the following is a full and clear specification.

This invention relates more especially to 10 portable searchlights in which provision is made to render such searchlights proof against the undesirable effects of water, smoke, dirt etc. The primary object of my invention is to provide improved means for 15 adapting a searchlight to transmit telegraphic signals. Other and further objects will appear in the specification and be pointed out in the claims, reference being had to the accompanying drawings which exemplify my invention in a preferred embodiment.

In the drawings,—

Figure 1 is a side elevation of a portable searchlight provided with my improvements;

Fig. 2 is a top plan view of the same;

Fig. 3 is a top plan view on an enlarged scale of the telegraphic key lever housing and key lever, said housing being partly 30 broken away;

Fig. 4 is a side elevation on an enlarged scale, of the upper right hand portion of Fig. 1, parts being broken away;

Fig. 5 is a front elevation on an enlarged 35 scale, of the telegraphic key and operating connections;

Fig. 6 is a wiring diagram.

Referring more particularly to the drawings, in the embodiment shown therein, the 40 handle 1 is suitably connected to a sheet metal housing 2 provided with a transverse partition 3 forming a battery chamber between it and the rear wall 4 of the housing. The battery chamber is provided with a 45 raised bottom 5 for supporting a storage battery at suitable elevation to be connected up to the sockets to be hereinafter referred to. A reflector housing 6 is journaled on an axis 7, so that light from a lamp 8 (see 50 Fig. 2) provided with a reflector 9, may be made to project light in any desired direction. The battery chamber is provided with a closure 10 which is hinged at 11 to the rear wall 4. Surmounting the closure 10

is a telegraphic key lever housing comprising portions 12, 13 and 14, portion 12 being rigidly mounted on the closure 10 and provided with a forward extension 12' for housing the contacts to be hereinafter referred to. The portion 13 is hinged to the portion 12 at 15, while the portion 14 is hinged at 16 to the portion 13 of this housing. Referring more particularly to Figs. 3 and 5, the telegraphic key lever 16 is trunnioned in spaced bearings 17 and provided with a finger pad 18 by means of which it may be oscillated for sending telegraphic signals. Conductor bars 19 and 20 may be connected respectively to key lever 16 and a conductor 21 which leads to the lower contact 22 of this telegraphic instrument. Conductor bars 19 and 20 terminate respectively in knife blade contacts 23 and 24. As shown in Fig. 5, the knife blades 23 and 24 coöperate respectively with the spring contacts 25 and 26 provided below with binding posts 27 (see Fig. 4). Referring to Fig. 6, the battery 28 has its terminals 29 and 30 connected respectively to lead wires 31 and 32, the former of which connects to one terminal 33 of a lamp 34. 80 The other terminal 35 of said lamp is connected by a wire 36 to a wire 37 which is connected at one end to one of the binding posts 27. In the diagram shown in Fig. 6, the binding posts 27 are represented as connected directly to the key lever 16 and conductor 21 respectively, the interposed conductors being omitted in this diagram. The wire 37 is connected at its other end to one of the terminals 38 of a switch 39, the other 85 terminal 40 of which is connected to a wire 41 leading to the other binding post 27, referred to above. Wire 32 from the battery 28 connects with this wire 41 making the circuit connections, as shown in Fig. 6. The 90 wires 31 and 32 leading from the battery terminals may be conducted through suitable sockets 43 and 44. Wires 37 and 41 leading from the binding posts 27, 27 to the terminals 38 and 40 of the hand switch 39, may 95 be conducted through suitable sockets 45 and 46, the connections between wires 32 and 41 and wires 36 and 37 being made as shown in Fig. 6. The finger grip 47 projects above the top wall of the housing 2 for operating 100 switch 39. The extension 12' of the telegraphic switch housing 12 serves to house the knife blade switches 23 and 24, together

with the spring switches 25 and 26 with which they coöperate.

The advantages of my improved construction will now be readily understood and 5 briefly related are as follows:

In places exposed to water, smoke, dirt, or other undesirable conditions, such as may be met with at a fire, for example, a 10 portable searchlight of the general character shown in outline in Figs. 1 and 2, is of great service. It becomes necessary, however, to protect the various parts connected with such a device from the smoke, water, dirt, etc. The details of construction of the 15 searchlight proper shown in Figs. 1 and 2 are shown, described and claimed in my copending application, filed February 9, 1917, Serial Number 147,603. The present application shows an improved construction 20 adapting it to be operated by a telegraphic instrument mounted directly on the searchlight, and in which the several parts are fully protected against the water, dirt, smoke, etc. Thus, should it be desired to 25 use this instrument to flash signals of light, the extension 14 of the telegraph lever housing may be swung on its hinge 16 to make the finger grip 18 accessible for flashing the light signals. During this operation, 30 hand switch 39 is, of course open, so that the electric circuit is periodically completed through the lever 16 and conductor 21. When it is necessary to gain access to the sending apparatus, the closure may be 35 swung about its hinge 15 to open up the housing 12. In order to adapt this telegraphic apparatus to be mounted directly upon the closure 10 of the battery chamber, the knife blade switches 23 and 24 carried 40 by the telegraphic apparatus, are made to coöperate with the spring contacts 25 and 26 mounted on the housing 2. The battery chamber may therefore be opened and closed at will. At the same time, the steady light 45 circuit may be utilized by closing the switch 39 whether the battery chamber is open or closed.

I claim:

1. In a portable searchlight, a lamp, a 50 storage battery, a housing for said storage battery provided with a movable closure, a telegraph key mounted on said closure, and an energizing circuit for said lamp, including said storage battery and said telegraph key, said circuit being provided with contacts opened and closed by the movement of said closure.

2. In a portable searchlight, a lamp, a storage battery, a housing for said storage battery provided with a movable closure, 60 a telegraph key mounted on said closure, an energizing circuit for said lamp, including said storage battery and said telegraph key, said circuit being provided with contacts opened and closed by the movement of said 65 closure, and a housing for said telegraph key mounted on the closure for said battery housing.

3. In a portable searchlight, a lamp, a storage battery, a housing for said storage 70 battery provided with a movable closure, a telegraph key mounted on said closure, an energizing circuit for said lamp, including said storage battery and said telegraph key, said circuit being provided with contacts opened and closed by the movement 75 of said closure, and a telegraph key housing comprising a main body mounted on the battery housing closure and an extension hinged to said main body.

4. In a portable searchlight, a lamp, a storage battery, a housing for said storage battery provided with a movable closure, a telegraph key mounted on said closure, an energizing circuit for said lamp, including 80 said storage battery and said telegraph key, said circuit being provided with contacts opened and closed by the movement of said closure, and a telegraph key housing comprising a main body mounted on the 85 battery housing closure and an extension hinged to said main body, said hinge being arranged on an axis parallel to the pivotal axis of the key lever.

5. In a portable searchlight, a lamp, a 90 storage battery, means for housing said lamp and storage battery, a telegraph key lever provided with a finger pad, and a housing for said key lever having a hinged portion for uncovering only said finger pad, 95 said key lever housing being provided with a hinged closure to which said hinged portion is pivotally connected.

6. In a portable searchlight, a lamp, a storage battery, means for housing said 105 lamp and storage battery, a telegraph key lever provided with a finger pad, and a housing for said key lever having a hinged portion for uncovering only said finger pad, 110 said means for housing the lamp and storage battery including a separate chamber for the battery having a closure to which said key lever housing is hinged.

JAMES W. KNOBLOCK.
